David Cochran,
BY John Diersheim.

ATTORNEY

UNITED STATES PATENT OFFICE.

DAVID COCHRANE, OF PHILADELPHIA, PENNSYLVANIA, ASSIGNOR TO THE HARRISON SAFETY BOILER WORKS, OF SAME PLACE.

FEED-WATER HEATER, PURIFIER, AND SEPARATOR.

SPECIFICATION forming part of Letters Patent No. 530,749, dated December 11, 1894.

Application filed April 20, 1894. Serial No. 508,342. (No model.)

To all whom it may concern:

Be it known that I, DAVID COCHRANE, a citizen of the United States, residing in the city and county of Philadelphia, State of Pennsylvania, have invented a new and useful Improvement in a Feed-Water Heater, Purifier, and Separator, which improvement is fully set forth in the following specification and accompanying drawings.

10 The object of my invention is to so combine in one structure a feed water heater and purifier and steam separator that they may serve the purpose of an expansion tank and return tank, besides doing their own work in 15 any system where exhaust steam is used in radiators or coils for heating or drying purposes, as will be hereinafter set forth.

Figure 1 represents a side elevation of a feed water heater and purifier embodying my 20 invention. Fig. 2 represents a front elevation, parts of the casing being broken away at the side to show the interior. Fig. 3 represents a plan view of Fig. 2, a portion being broken away to show the construction of the 25 separator.

Similar letters of reference indicate corresponding parts in the several figures.

Referring to the drawings: A designates the feed water heater inclosed by a casing to 30 which is suitably secured the steam separating device B, which has the baffle plates C, which are located in the path of the incoming steam, and serve to arrest any impurities in the same.

35 D designates an exhaust steam inlet.

E designates a drip pipe leading downwardly from the separator into the waste pipe F, which enters the bottom of the box G, which has the function of a steam trap, and is attached to the side of the casing A, having an opening covered by the flange H for the insertion of the float J. The flange H has a hollow boss K cast thereon, which carries the arm L, one end of which is suitably connected 40 to the rod L² which is attached to the float J, while the other end is secured to the arm M, which is suitably connected to the stem of the regulating valve N, in such a way that any variation of level of the water in the 45 50 trap G will through the medium of the float and intervening mechanism, cause the valve

to move so as to increase or retard the flow of water from the trap G through the waste pipe F, to which is attached the blow-off pipe P, which leads from the bottom of the tank, 55 and is provided with the valve Q. The trap G is open to the inside of the heater through the skimmer R, over which projects the deflecting plate S.

T designates a gage for indicating the 60 height of water in the trap G, and U designates a gage for indicating the water line of the main heater.

V designates a man-hole near the bottom of the casing.

W designates the return pipe of the system, and X designates the base of a combined water box and tray on the inside of the heater, which extends from side to side of the same.

Y designates a partition, the edge of which 70 is serrated or saw-toothed, and extends upwardly so there is always a water seal over the return opening, thus preventing any steam from leaving the heater through the return pipe W, or interfering with the flow of water 75 therein. The edge Z of the tray is also serrated or saw-toothed, so that as the return water flows over the edges Y and Z, it will fall in the form of finely divided streams, which will mingle freely with the steam until 80 they are both of approximately the same temperature, before it drops into the tank below, from which it is pumped to the boiler through the pipe A', which leads to a feed pump.

In the upper part of the heater are located 85 the deflecting plates B', C', D', &c., which are arranged alternately, and break into finely divided streams, the cold water flowing on to them from the cold water inlet pipe E' which is provided with a regulating valve F', which 90 is connected by means of its stem G' and link H', and other suitable intervening mechanism, similar to that shown in connection with the float in the trap G, to the float K', so that any variation of water level in the tank, will 95 cause the regulating valve F' to either open or close, thus increasing or decreasing the flow of cold water into the tank.

L' designates a hood extending downwardly to near the bottom of the tank.

M' designates doors for providing access to the deflecting plates or trays.

N' designates the highest water line which can be reached, any water rising to a higher level flowing into the skimmer R , and thence to the steam trap G .

5 O' designates the normal or working water line.

In dotted lines at the top of Fig. 2, P' designates a pipe leading from the heater to the atmosphere, and Q' designates a back pressure valve placed in it, beyond the last connections R', R' that are taken from it to radiators or coils. A connection is also made to any of the steam heating pipes inside of the back pressure valve from a boiler or live steam pipe 15 S' , in which is a reducing valve T' , set to a lower pressure than the back pressure valve Q' , so that there will be no chance of steam blowing through it to the atmosphere. The object of this live steam inlet is to introduce 20 live steam to supplement the exhaust if there is not enough to supply the demands of the radiators. Should there be more exhaust than the radiators will condense, the pressure will increase until it is high enough to open the 25 back pressure valve, the surplus escaping to the atmosphere.

The operation will now be apparent. The water of condensation from the heating system enters the heater through the pipe W , 30 which leads into the combined box and tray, which is so constructed that the return opening is always sealed with water, thus preventing any steam from leaving the heater through said return pipe, and thus interfering with 35 the flow of water therein. As the return water flows over the serrated edges Y and Z , it will be broken up into small streams which will mingle freely with the incoming steam until they are both of approximately the same temperature, before falling into the tank below, 40 whence it is pumped to the boiler through the pipe A' . If the return water is not enough to supply the demands of the pump, then the water level begins to fall in the tank, lowering 45 the float K' , and opening the regulating valve F' in the cold water supply pipe E' , which will admit enough cold water to make up any deficiency, this cold water being heated by mingling with the exhaust steam 50 in its downward flow over the plates or trays $B', C', D', &c.$ Should more water accumulate in the heater than is being pumped back to the boilers, the water level in the tank will rise until it reaches the top of the skimmer 55 R , over which it will flow into the trap G , raising the float J , which by means of its intervening mechanism, will lift the valve N in the waste pipe, thus allowing any surplus water to leave the heater. Water or oil from 60 the separator B passing through the pipe E acts in the same way on the float with the same results, and it will be seen that water or oil from the heater or separator can never accumulate so as to interfere with the free flow 65 of steam through the heater.

Exhaust steam enters the heater through the pipe D , passing through the separator B ,

where any entrained oil or water is separated, and is conducted through the pipe E to its waste pipe F , as has been hereinbefore described. 70

The pulsations of the exhaust will be dissipated in the heater, as there is ample room for the variations of pressure to equalize and keep a steady flow of steam through the exhaust pipe at the top, which leads to the atmosphere and which is provided with the back pressure valve Q' , and the auxiliary live steam pipe, the function of which parts has already 80 been set forth.

Some parts of the heater and of the steam separating device are substantially the same as described in my patents of March 3, 1885, and February 4, 1890, and to these I make no claim. 85

Having thus described my invention, what I claim as new, and desire to secure by Letters Patent, is—

1. The herein described water seal box and tray, having a base X , and the serrated partitions Y and Z , arranged at an angle thereto said box being adapted to be attached to a heater, substantially as described. 90

2. A water seal box and tray provided with a base X , and the partitions Y and Z adapted 95 to be attached to the interior of a feed water heater, substantially as described.

3. A feed water heater, a steam separator, and a steam trap suitably attached thereto, and independent passages leading from the 100 heater and separator to the same, said trap being provided with a valve, waste pipe, and float-actuated mechanism communicating therewith, said parts being combined substantially as and for the purpose set forth. 105

4. A feed water heater, a steam separator and trap attached thereto, independent passages from the separator and heater leading to the trap, float-actuated mechanism for relieving the trap of any accumulation of water, and a water seal device located opposite the return pipe of the heater, said parts being combined substantially as described. 110

5. In a feed water heater, having a return pipe, a water seal box and tray adjacent 115 thereto, a pipe leading to a feed pump, an inlet for exhaust steam above the water level of the heater, a cold water supply pipe for the heater, float-actuated mechanism connected to the cold water supply pipe, whereby any 120 lowering of the water level in the tank will cause an inflow of cold water, and vice-versa, substantially as described.

6. In a feed water heater, having a return pipe, a water seal box or tray adjacent 125 thereto, a pipe leading to a feed pump, an inlet for exhaust steam above the water level of the heater, a cold water supply pipe for the heater, a hood projecting over said pipe, leading to the feed pump, float-actuated mechanism connected to the cold water supply pipe, 130 whereby any lowering of the water level in the tank will cause an inflow of cold water, and vice-versa, substantially as described,

7. A feed water heater provided with a separator, and a trap attached thereto, independent passages leading from the separator and heater to said trap, float-actuated mechanism, whereby any undue accumulation of water in the trap is prevented, a water seal placed adjacent to the return pipe inlet, a cold water inlet pipe, float-actuated mechanism connected therewith, said parts being combined substantially as described.

8. In a feed water heating device of the character described, a pipe P' leading to the atmosphere, a back pressure valve therein, pipes below said valve leading to radiators or heating systems, an auxiliary live steam pipe S' entering the pipe P', below the back press-

ure valve, provided with a reducing valve T', set at a lower pressure than the back pressure valve, said parts being combined substantially as and for the purpose set forth.

20

9. A feed water heater, a steam separator, and a steam trap attached thereto, and independent passages leading from the heater and separator to said trap, the passage leading from the heater being provided with a valved waste pipe, and float actuated mechanism operating therewith, said parts being combined substantially as described.
